ELECTRIC DRIVING MECHANISM

Filed May 31, 1927

INVENTOR.
Andrew H. Neureuther

UNITED STATES PATENT OFFICE

ANDREW H. NEUREUTHER, OF PERU, ILLINOIS, ASSIGNOR TO WESTERN CLOCK COMPANY, OF PERU, ILLINOIS, A CORPORATION OF ILLINOIS

ELECTRIC DRIVING MECHANISM

Application filed May 31, 1927. Serial No. 195,490.

My invention relates to electrical driving mechanisms and has for its object the production of a driving mechanism for clocks and similar devices, particularly automobile clocks or clocks that are used on or in connection with apparatus and equipments that already have and use electrical power generating or storing means to operate other electrical devices on same and where a comparatively large amount of the total available current is used for said other purposes for instance in case of the automobile for starting the motor and for the operation of the lights on the car and even in houses, factories etc. where electricity is now so universally used. In my invention the electrical current is used intermittently for a very short period of time actuating an electrically operated mechanism which transforms the power of said current into mechanical power and stores it in a mechanical storing means to be used as required in the device driven by it.

A further object of my invention is to overcome the difficulties that before my invention made such clocks impractical because the large currents necessary to operate them at the usual low voltages employed on such mediums always burnt up or damaged the current closing and breaking contact points so that after a very short period of operation they would weld together and stick or oxidize and fail to conduct the currents even though said contact points were made of or covered with the noble metals such as platinum and silver. My object is to eliminate these expensive contacts and the unsatisfactory operating conditions by using a new extremely quickly actuated closing and opening device in which the said contacts are made with a definite decided wiping or sliding motion, which motion is continued for a definite distance after the contact is made insuring a continuous cleanly wiped, practically polished contacting surface enabling the use of

ordinary commercial metals thereby producing a substantial lasting and practical device which because of this and its simple construction is very inexpensive to produce.

Another object of my invention is to produce such a driving mechanism that will be sufficiently rugged and definitely positive in operation so that it will meet the severe requirements necessary in automobile service.

In the drawings: Fig. 1 is a view of one of my driving mechanisms looking at it from the rear and having sufficient of the rear plate removed to show the operative mechanism with the armature of the magnet in its highest position and ready to be actuated by the magnet.

Fig. 2 is a similar view of my driving mechanism showing the armature of the magnet approaching its lowest position after it has been actuated by the magnet.

Fig. 3 is a view of a modification of my driving mechanism showing same in a view similar to the view shown in Fig. 1.

Fig. 4 shows a top view of the contact mechanism wherein the electrical contact is made by the side wiping of the contacting members instead of making the contact on the rear and front of the contacting members respectively.

Fig. 5 is a top view of Fig. 2 showing my driving mechanism attached to a clock or time indicating device.

Similar numerals represent the same parts through the several views.

In the drawings, 1 represents one plate and 2 the other plate of a containing frame of my driving mechanism as shown which plates are suitably spaced and fastened together by means of pillar posts 3. Said plates 1 and 2 each have an aperture adjacent to or at their centers in and through which is journaled an arbor or shaft 4. On one end of arbor 4 is fastened a suitable coupling or resilient member 5, by means of which any power or force communicated to arbor 4 is transmitted to drive a clock or other like mechanism, or to

some power storing mechanism such as a spring and the like from which power or force storing mechanism the power or force can be transmitted to the driven device. Fas-
5 tened on the other end of arbor 4 is a ratchet wheel 6 having a suitable number of teeth 7 which teeth 7 are in continuous engagement with a suitably shaped floating pawl 8 which is pivotally mounted on the arm 10 of a suit-
10 ably shaped armature 9 by means of a pin or bolt 11. Pawl 8 has a projecting hook 12 to which is attached a suitably formed spring 13 whose opposite end is fastened to bolt 14 which is suitably mounted in an aperture in
15 a member 15 projecting from either one of said plates, by means of the nuts 16 shown. It is evident that the tension of said spring 13 keeps the pawl 8 in continuous engagement with the teeth 7 of ratchet wheel 6 and it is
20 further evident that the tension of said spring 13 can be controlled by means of the bolt 14 and the nuts 16. A pawl 43 adjacent to ratchet wheel 6 engaging teeth 7 is pivotally connected to the plate 2 by means of a pin 44 and said pawl 43 is held in engagement with said teeth 7 by means of the spring 45 fastened to said plate 2 as shown. Said pawl 43 keeps ratchet wheel from going backwards during the changing of the power storing mechanism.
25 The armature 9 in addition to the arm 10 formed on one edge has a shorter arm 17 formed on the other edge opposite to the arm 10. Arms 10 and 17 have the apertures shown adjacent to the body part of armature
30 9 in which apertures are journaled pins 18 each one fastened to one of the plates 1 and 2 or 18 can be a rod passing through apertures in plates 1 and 2 and the apertures in said arms 17 and 10, depending rather upon the
35 facility for assembling or putting the parts of the device together.

Formed integrally with and projecting upwardly from the edges of armature 9 are the
40 lugs 19 each having an aperture as shown in which is journaled an arbor 20 having a head 21. On the end of arbor 20 opposite head 21 is fastened a suitably shaped plate 22 having a slot or elongated aperture 23 in its forward end and a similar slot or elongated aperture 24 on its rearward end as shown. Member 22 also has formed integrally with it a projection 25. Armature 9 also has an additional member 26 preferably formed integrally with it at a point adjacent to slot
45 24 in member 22 and 26 has the aperture shown in which is fastened a stop pin 27 which pin 27 projects into the slot 24 and thus limits angular distance the member 22 can rotate on the arbor 20. Projecting from and
50 preferably formed integrally with armature 9 is a member 28 having an aperture 29 in which is pivotally fastened one end of a suitably shaped spring 30 the other end of which is similarly pivotally fastened to a
55 projection or pin 31 fastened to the above
60

mentioned pivotally mounted member 22. The spring 30 can be a coiled spring or any of the usual springs well known and used in the art and the fastening or connection used on member 28 and member 22 will register with the type of spring used. The only requirement of the spring is that it will operate to pull the part 31 toward the projection 28. Part 31 on member 22 is located to the right of the arbor or pivot 20 and the projection 28 is located to the left of said arbor or pivot 20 and the spring 30 operates to pull part 31 toward projection 28, and further the pivoted point 20 when member 22 is in its central position is located on the line from the center of aperture 29 and the center of pin 31. It is evident from these located points and the spring pull as above mentioned that when pin 31 moves out of said central position and reaches a point above said central line the member 22 will be snapped or quickly rotated to the left (counterclockwise) until the upper side or limiting part of slot 24 comes against the pin or part 27 and the part 25 of member 22 is in the position shown in Fig. 2 and completely away from its component contacting member 32. Should it be found more convenient to locate the pin or part 31 to the left of the arbor 20 then it is evident that the spring 30 can be of any type that will push (act by compression instead of tension) instead of pulling as above mentioned, the idea being to locate the point of application 31 and the type of spring 30 so that the member 22 will be suitably partially rotated around the arbor 20 whenever the center of part 31 passes beyond either side of the above mentioned central line from the center of aperture 29 and the center or arbor 20. This contacting member 32 is preferably formed of resilient electrical conducting material which is mounted on plate 1 as shown but electrically insulated therefrom by means of the insulating material 33 and is electrically connected with the winding wire 35 on the electro-magnets 36 by means of a conducting wire 34. The winding wire 35 is connected to an electrical connecting post 37 on plate 2 by means of a wire 38, as shown. Post 37 is electrically insulated from the plate 2 by any of the usual insulating mediums used in the art and said post 37 is always connected to one of the wires from the electrical source of current, the current circuit being completed by connecting or "grounding" the other wire from the electrical source of power to the plates 1 or 2 of the frame work and as all the parts above described are formed of metal and conduct electricity it is evident that if any part of the armature 9 or its appendages such as projecting member 25 comes into contact with the component or co-operating contact member 32 the electrical current will flow through the magnet 36 and cause the armature 9 to be drawn toward

70 75 80 85 90 95 100 105 110 115 120 125 130

it, and rotate said armature 9 on the pivot or arbor 18, which in turn stretches the spring 13 storing the power or force exerted by the magnet and as soon as the electrical current is cut off (by means described below) which de-energizes said magnet 36 said spring 13 imparts said force or power by means of the pawl 8 to ratchet wheel 6, the arbor 4 and the power transmitting or coupling means 5.

10 It is seen that the armature 9 partially rotates on arbor 18 and that the part 22 being pivotally mounted on 9 near its end also moves with it so that when projection 25 and its component or co-operating member 32, are in contact it is evident that because of the sliding motion produced by the movement of projection 25 on said member 32 the point of contact will always be wiped clean and be bright so that the electrical contact and conduction will be maintained perfect at all times.

Fastened to one of the plates 1 or 2, or both of said plates, is a pin or rod 39 which is suitably located so that it passes through the slot 23 at such a point so that as power spring 13 shortens and gives out its power to arbor 4 allowing the armature 9 and pivoted part 22 to rise until the lower or limiting edge of slot 23 comes against pin 39 where 25 as the armature 9 continues to rise the pivotally mounted member 22 starts to rotate in right hand or clock wise direction until the pin 31 reaches a point sufficiently below the center line through centers of arbor 20 30 and aperture 29 when the spring 30 snaps member 22 around so that projection 25 engages its component and co-operating member 32, which closes the circuit which energizes the electro-magnet which immediately 35 pulls the armature and the above mentioned member 22 downwardly toward the magnet so that the upper or limiting side of the slot 23 strikes the pin 39 (the slot 23 also being sufficiently wider than the diameter of the 40 pin to permit a considerably reasonable amount of motion before the upper side of the slot strikes the pin 39) keeping the contacts mentioned together until the magnet has been energized sufficiently long to permit the required motion of the armature and give it 45 sufficient momentum to carry it onward until the pivoted member 22 is rotated in counter-clock-wise direction (or to the left in its upper part) sufficiently so that the pin 31 is brought far enough above the central line 50 from centers of arbor 20 and aperture 29 to cause the spring 30 to snap it into the position shown in Fig. 2 separating the contacting parts 25 and 32 which de-energizes the 55 magnet which has just put its power into spring 13 and permits said spring 13 to again give up its stored power or force to arbor 4 as above mentioned said operation being continued as long as the driving mechanism is 60 connected to a source of electrical current.

In the modification shown in Fig. 3 the armature 9 has a suitably formed projection 40 which may be formed integrally therewith, which projects into the magnetic field of the magnet 36 which magnets are positioned as shown and when energized in the manner above mentioned similarly pull the armature 9 around the pivot 18 and actuate the mechanism all as above described. 41 is a limiting and dampening means which prevents the armature 9 from over traveling when the magnet is energized and breaking the contact operating parts mounted on it as well as to prevent the noise caused by the moving metal parts striking on other surfaces. It is evident that the part 22 can be similarly mounted on armature 9 adjacent to the point where the projection 40 is attached thereto in the same way that it is shown mounted on the armature 9 in Figures 1 and 2 and actuated similarly all as above described. 42 is a usual clock or time indicating mechanism. By connecting my mechanism to the shaft that carries the minute hand and having 60 teeth on the ratchet wheel 6, it will be seen that the magnet 36 will be energized once each minute, so that the same current that energizes the magnet 36 could also actuate any system of the well known electric secondary clocks, either directly or 95 indirectly by use of a suitable relay.

It is evident from the above description that my driving mechanism is very simple and inexpensive to construct, very durable and easy to maintain and requires only to be made of the usual ordinary metals even as to the contact points for the action of the contacting device is extremely quick and snappy in making the initial contact and in the breaking of the circuit and further after 100 the initial contact is made the making contact point slides along its component and co-operative member thus keeping both contact members wiped and clean for further continuous contact operations which make my 105 invention continuously operative at all times because it prevents oxidizing as well as welding and sticking of the contact points which was so much in evidence in electric clocks 110 of this type before my present invention.

It will be understood of course, that while I have here shown one form of my invention, I do not wish to limit myself to the exact construction shown, but rather to have it taken in a sense illustrative of any or all 120 the forms of same as come fairly within the scope of my claims.

I claim:

1. In a driving mechanism, an electro-magnet, an armature mounted adjacent to said magnet, power storing means connected with and actuated by said armature, a member having a plurality of slots pivotally mounted on said armature, resilient means on said armature for controlling the positions of 125 130 135

said member in combination with a contacting part and external means in one of said slots co-operating with said resilient means to bring said member into engagement with said contacting part.

5 2. In a driving mechanism, an electro-magnet, an armature mounted adjacent to said magnet, power storing means connected with and actuated by said armature, a member having a plurality of slots pivotally mounted on said armature, resilient means on said armature for controlling the positions of said member in combination with a contacting part and external means in one of said slots co-operating with said resilient means to bring said member into engagement with said contacting part intermittently.

20 3. In an appliance of the character described, a frame, an electro-magnet mounted on said frame, an armature pivotally mounted adjacent to said magnet, power storing means connected with and actuated by said armature, a member having a plurality of slots pivotally mounted on said armature, resilient means on said armature for controlling the limiting positions of said member, a contacting part on said frame and means on said frame co-acting with said member bringing said member into electrical engagement with said contacting part.

25 4. In a driving mechanism, a frame, an electro-magnet mounted on said frame, an armature pivotally mounted adjacent to said magnet, power storing means connected with and actuated by said armature, a member having a plurality of slots pivotally mounted on said armature, means on said armature co-acting with one of said slots limiting the motion of said member, resilient means on said armature for controlling the limiting positions of said member, a contacting part mounted on said frame but electrically insulated therefrom, and means on said frame co-acting with said member bringing said member into electrical engagement with said contacting part.

30 5. In a driving mechanism, a frame, an electro-magnet mounted on said frame, an armature pivotally mounted adjacent to said magnet, power storing means connected with and actuated by said armature, a member having a plurality of slots pivotally mounted on said armature, means on said armature co-acting with one of said slots limiting the motion of said member, resilient means on said armature for controlling the limiting positions of said member, a contacting part mounted on said frame but electrically insulated therefrom, and means on said frame co-acting with a slot on said member bringing said member into electrical engagement with said contacting part.

35 6. In a driving mechanism, a frame, an electro-magnet mounted on said frame, an armature pivotally mounted in said frame ad-

jacent to said magnet, power storing means connected with and actuated by said armature, a member having a plurality of apertures pivotally mounted on said armature, a pin suitably mounted on said armature projecting into one of said apertures limiting the motion of said member, suitably positioned resilient means on said armature for bringing said member against said pin on said armature, a contacting part mounted on said frame, a pin mounted in said frame projecting into one of said apertures on said member co-acting with said resilient means on said armature for bringing said member into electrical engagement with said contacting part.

40 7. In a driving mechanism, a frame, an electro-magnet mounted on said frame, an armature pivotally mounted in said frame adjacent to said magnet, power storing means connected with and actuated by said armature, a member having a plurality of apertures pivotally mounted on said armature, a pin suitably mounted on said armature projecting into one of said apertures limiting the motion of said member, suitably positioned resilient means on said armature for bringing said member against said pin on said armature, a contacting part mounted on said frame but electrically insulated therefrom, a pin mounted in said frame projecting into one of said apertures on said member co-acting with said resilient means on said armature for bringing said member into electrical engagement with said contacting part.

45 8. In a driving mechanism, a frame, an electro-magnet mounted on said frame, an armature pivotally mounted adjacent to said magnet, power storing means connected with and actuated by said armature, a member having a plurality of apertures pivotally mounted on said armature, a pin mounted on said armature projecting into one of said apertures, resilient means on said armature connected to said member, a contacting part mounted on said frame, and mechanism on said frame engaging one of the apertures on said member co-acting with said resilient means on said armature bringing said member into electrical engagement with said contacting part maintaining said engagement for a definite period during the movement of said armature toward said magnet.

50 9. In an electric driving mechanism, an electro-magnet, an armature associated with said electro-magnet, power storing means associated with said armature, a contacting lever mounted on said armature, resilient means associated with said lever, a co-operative contacting part co-acting with said lever, an electrical circuit associated with said magnet and actuating means directly co-acting with said lever to move said lever relatively to said armature.

55 10. In an appliance of the character de-

scribed, a frame, an electro-magnet mounted on said frame, an armature pivotally mounted adjacent to said magnet, power storing means connected with and actuated by said armature, a member having a plurality of projections pivotally mounted on said armature, means on said armature for limiting the motion of said member, a contacting part on said frame and an abutment on said frame directly co-acting with said member for bringing said member and said contacting part into electrical engagement.

ANDREW H. NEUREUTHER.
